CLAIM

The ornamental design for a drain channel, as shown and described.

DESCRIPTION

FIG. 1 is a front perspective view of the invention;

FIG. 2 is a bottom plan view of the FIG. 1; and,

FIG. 3 is a rear elevation view of FIG. 1.

The broken lines, shown in the drawings, depict portions of the drain channel and form no part of the claimed design.

1 Claim, 2 Drawing Sheets
